BED GUARD

Josephine Di Bella Herz and Harry Herz,
Fort Pierce Beach, Fla.

Application October 26, 1951, Serial No. 253,334

5 Claims. (Cl. 5—331)

1

This invention relates to new and useful improvements in beds for infants and children and relates more particularly to a novel attachment for beds which will instantly convert the bed into an arrangement which is suitable for young children who have outgrown the crib stage but who nevertheless have need for side guarding devices to prevent them from rolling out of the bed.

An important object of the present invention is to provide a novel bedside guard which will quickly convert an ordinary bed, consisting of a spring and mattress, with or without a head board, into a child's bed which prevents the child from falling off the bed, much in the same manner as the known "youth" beds but which does not alter the structure of the conventional bed and which permits the latter to be instantly reconverted back to its former status.

Another object of the invention is to provide a bed guard which can be shipped or stored in flat condition while occupying little space and can instantly be set up for use to provide a rigid and safe guard.

In the drawings:

Fig. 1 is a perspective view of an embodiment of the present invention;

Fig. 2 is a broken section taken on line 2—2 of Fig. 1;

Fig. 3 is a broken perspective view showing the method of securing the side boards to the head board;

Fig. 4 is a perspective view showing a modified form of the invention;

Fig. 5 is a broken section taken on line 5—5 of Fig. 4;

Fig. 6 is a fragmentary view of a portion of the device.

Referring now more particularly to the drawing, the first embodiment of the invention shown in Figs. 1, 2 and 3, includes a head board 10 and side boards 11 and 12. For convenience in shipping and storage, the parts are made demountable and to this end the side boards are provided on their rear edges with lugs 13 which are received in recesses 14 on each side of the head board. When the parts are secured in place the head board gives approved rigidity to the side boards.

The latter are further connected at their outer ends by a cross-piece 15 which may be made from fabric. A similar cross-piece 16 is secured at the opposite ends of the side board.

The width of the head board is substantially the same as the width of the bed spring 11, which latter is shown as being mounted on legs 18. Thus, the side boards and head board are sup-

2

ported by the edges of the spring. The height of the side boards is about two times the thickness of the mattress shown at 19. Thus, after the bed guard of the present invention has been placed on the spring, the mattress is arranged in place as shown in Fig. 2 and the latter holds the cross-pieces and the whole structure firmly in place. Also, the sides of the mattress engage the side boards.

The modified structure of Figs. 4, 5 and 6 is arranged for use on a bed which is already provided with a fixed head board shown at 20. The side boards 21 and 22 are again connected by the flexible cross-pieces 23 and 24. In this instance, however, the rear terminals of the side boards are connected by a member 25 which may be a flexible strap made from the same material as the cross-pieces.

This structure, while not so rigid as the first one, nevertheless gives good results since normally there is no great strain imposed on the side boards.

While two forms or embodiments of the invention have been shown and described herein for illustrative purposes, and the construction and arrangement incidental to two specific applications thereof have been disclosed and discussed in detail, it is to be understood that the invention is limited neither to the mere details or relative arrangement of parts, nor to its specific embodiments shown herein, but that extensive deviations from the illustrated forms or embodiments of the invention may be made without departing from the principles thereof.

We claim:

1. A bed guard of the character described comprising a plurality of spaced side boards arranged to extend along opposite sides of a mattress which is supported on a spring, a cross-piece extending from one side board to the other and passing between the mattress and the spring, and means connecting the rear terminals of the side boards to give rigidity to the same, the side boards being of lesser length than the mattress and being of greater height than the same.

2. A bed guard of the character described comprising a plurality of spaced side boards arranged to extend along opposite sides of a mattress which is supported on a spring, a plurality of cross-pieces of flexible material extending from one side board to the other and arranged to pass between the mattress and the spring, and means connecting the rear terminals of the side boards to give rigidity to the same, such means comprising a head board and detachable fastening means for securing the members to-

gether, the side boards being of lesser length than the mattress and being of greater height than the same.

3. A bed guard of the character described comprising a plurality of spaced side boards arranged to extend along opposite sides of a mattress which is supported on a spring, cross pieces extending from one side board to the other and arranged to pass between the mattress and the spring and means comprising a head board connecting the rear terminals of the side boards to give rigidity to the same, the side boards being of lesser length than the mattress and being of greater height than the same.

4. A bed guard of the character described comprising a plurality of spaced side boards arranged to extend along opposite sides of a mattress which is supported on a spring, a cross piece extending from one side board to the other and arranged to pass between the mattress and the spring, and a head board for connecting the rear terminals of the side boards to give rigidity to the same, detachable fastening elements between such terminals and the head board, the side boards being of lesser length than

20 25

the mattress and being of greater height than the same.

5. A bed guard of the character described comprising a plurality of spaced side boards arranged to extend along opposite sides of a mattress which is supported on a spring provided with a head board, a cross piece extending from one side board to the other, and arranged to pass between the mattress and the spring, and means extending to the rear of the head board connecting the rear terminals of the side boards to give rigidity to the same, the side boards being of lesser length than the mattress and being of greater height than the same.
